FOREIGN PATENT DOCUMENTS

U.S. Appl. No. 61/898,062 to Dixon et al. filed Oct. 31, 2013, entitled *Eyewear Article Side Shield Retainer*.

(Continued)

Primary Examiner — Raphael Barkai

(74) *Attorney, Agent, or Firm* — Peter L. Olson

(57) **CLAIM**

The ornamental design for an eyewear article side shield retainer, as shown and described.

DESCRIPTION

FIG. 1 is a front perspective view of a new design for an eyewear article side shield retainer.

FIG. 2 is a front view thereof;

FIG. 3 is a back view thereof;

FIG. 4 is a right view thereof, the left view being a mirror image thereof;

FIG. 5 is a top view thereof; and,

FIG. 6 is a bottom view thereof.

Broken lines form no part of the claimed design, and any shading is provided to illustrate contour only and is not an indication of texture, gloss, etc.

1 Claim, 3 Drawing Sheets
